CLAIM

The ornamental design for a syringe pump housing, as shown and described.

DESCRIPTION

FIG. 1 is a front bottom right perspective view of a syringe pump housing showing my new design;

FIG. 2 is a front bottom left perspective view thereof;

FIG. 3 is a front elevation view thereof;

FIG. 4 is a rear elevation view thereof;

FIG. 5 is a left view thereof;

FIG. 6 is a right view thereof;

FIG. 7 is a bottom plan view thereof; and,

FIG. 8 is a top plan view thereof.

The dashed lines of even length depict portions of the syringe pump housing that form no part of the claimed design. The dash-dot-dash broken lines depict the boundary of the claimed design, and form no part of the claimed design.
